UNITED STATES PATENT OFFICE.

FRANZ WONDRA, OF SCHENECTADY, NEW YORK.

AEROPLANE.

1,250,262.

Specification of Letters Patent.

Patented Dec. 18, 1917.

Application filed March 19, 1909, Serial No. 484,580. Renewed May 29, 1917. Serial No. 171,763.

To all whom it may concern:

Be it known that I, FRANZ WONDRA, a citizen of the United States, residing in Schenectady, in the county of Schenectady and State of New York, have invented certain new and useful Improvements in Aeroplanes, of which the following is a specification.

The invention relates to an improved aeroplane and is in the nature of an improvement of a flying-machine shown and described in my Patent No. 876,125, Jan. 7, 1908.

The objects of this invention are to provide means for automatically maintaining the longitudinal and lateral stability of the aeroplane, to increase the lifting effect of the sustaining surfaces without increase of power, to afford facilities for the absorption 15 of the wind gusts and further to provide a structure combining lightness with strength, and certain novel features which will be more fully described hereinafter and pointed out in the claims.

25 I attain these objects by the shapes and arrangements of the planes and mechanism illustrated in the accompanying drawings in which—

Figure 1 is a side view of the entire aeroplane; Fig. 2 is a plane view of the same partly broken away; Fig. 3 is a rear view of the aeroplane also partly broken away; Fig. 4 is a outline side view of the aeroplane with superposed planes; Fig. 5 are sections 35 of one of the planes at different cross ribs, and Fig. 6 is a side view of one of the cross ribs.

The aeroplane consists of a plurality of inclined planes (three in this case) arranged 40 in succession and in gradation, the first plane being the lowest, two propellers placed one above another under and above the rear plane and located so that the thrust comes through the line of resistance of the apparatus, a short plane placed above the upper propeller, a rudder under the front plane, a motor placed near the center of gravity of the apparatus, a seat for the operator, a shifting gondola, a running truck, steering 45 gears and floats. The supporting main frame 1 is made of steel tubing or wood and comprises two pairs of parallel tubes or spars lowered forwardly so as to suit the location of the planes, which are connected together by transverse spars, forming thus a frame body quadrangular in cross section.

To this central frame are fastened upright standards or struts 2, extending upwardly and downwardly, which serve to support the different parts of the apparatus. The lowest ends of these struts are connected by horizontal tubes or spars 3, which bear the running gears, floats and serve at the same time as guideways for the shifting gondola. Between the middle plane and the shifting 65 gondola is built in the main frame an engine-bed 4 and platform 5.

In the front of the frame is mounted the rudder 6 so supported as to turn around its vertical axis in the center of its area. 70

On the transverse members between the standards, of the last plane are supported bearings for the propeller shafts and driving gears.

The shape of the planes, 7, 7^a, 7^b can be 75 readily seen from the drawings. On the transverse rib 8, which is attached to the main frame and supported by stay wires 9, are fastened wooden cross ribs 10, equally spaced.

The front margin of the plane is convex in plan view, the rear margin from the middle of the plane is concave and shorter than the front margin and both are connected by a short concave margin on both ends. The 80 edges of the plane are tapering from the center toward their ends. The transverse rib can be placed at right angles to the main frame. Each plane is made of two halves like a wing of a bird and each half is attached separately to the frame and standards. The curvature of the wooden cross ribs can be seen in Fig. 5. 85

Each plane is inclined at a suitable angle of incidence to the line of motion and the 90 inclination is decreasing from the middle of the plane toward its ends. The plane is slightly curved in lateral direction and the front edge is with respect to the horizontal bent down from the longest cross-rib and the 95 rear edge is bent upward.

All the planes are alike in shape but different in the inclination and area. The front plane is the smallest one with the largest angle of incidence, the middle plane 100 is larger in area, but has smaller angle of incidence and the rear plane is larger in area than the middle plane with still smaller angle of incidence.

The planes are mounted on the frame in 110 succession, the second being higher above the horizontal than the first one and the third

plane higher than the second. The distance between the second and third planes is greater than between the first and second planes. The objects of this adjustment will 5 be more fully described hereinafter. There are three planes employed but two or more planes will obtain the same effect.

The rear plane is cut out on account of the upper propeller and an additional short 10 plane 11 is placed above the upper propeller to compensate for the lost surface. A narrow plane may be also placed under the lower propeller.

The arrangement for forming the sustaining 15 surfaces by stretching cloth or other suitable material over the wooden ribs can be seen in Fig. 6.

The cloth of each plane is cut approximately to the size and shape of the plane, 20 light steel tubes or wooden spars are sewed into the lateral margins of the plane. The ribs have on both ends metallic hulls 12, to fit the said marginal tubes or spars and the so stretched cloth is fastened by the clamps 25 13, underneath the wooden ribs. The wire 14 connects the both clamps securing thus the given curvature of each rib.

The cross ribs are secured to the transverse main rib by metallic joints 15. Each 30 plane is supported by stay wires 16 and by fastening the second cross ribs to the main frame in their given inclination to the horizontal. For large size apparatus two transverse ribs should be employed and for covering 35 the planes metal sheets should be used.

The aeroplane is driven against the air by two superposed propellers 17, revolving in opposite directions in the rear of the transverse rib of the last plane. The propellers 40 are placed under a plane and are therefore more efficient. Rotary motion is imparted from the motor 18 to the shaft of the lower propeller and transmitted from the same to the shaft of the upper propeller 45 by means of gears on shafts, or other power transmitting means.

The steering of the aeroplane to right or left is accomplished by a rudder 6, stiffened by wire 19 and placed under the front plane, 50 so supported as to turn around a vertical axis near the center of its area. The rudder is operated by the operator from the seat 20, by the hand-wheel 21, which is fastened to a tubular rod with a bevel gear 22 on its lower end. The connecting rod 23 is equipped with a bevel gear 24 which meshes with gear 22 and on the other end, is a worm 55 25 which meshes with the worm-gear 26 fastened on the vertical axis of the rudder.

60 This arrangement secures easy control of the rudder, which also serves, being always locked in desired position, to the line of flight, for maintaining the lateral stability of the aeroplane.

65 The steering in the vertical direction is ac-

complished by changing the center of gravity of the aeroplane by means of shifting the gondola 27 forward or backward on the wheels 28 along the guideways 3, which connect the upright struts of the main frame. 70

The position of the sliding gondola is changed by the handwheel 29, which is mounted above the handwheel 21 on a tubular rod passing through the first wheelrod. A connecting rod 30 having on one end a 75 bevel gear 31, which meshes with a gear 32 on the handwheelrod and having a worm 33 on the other end, which imparts motion to the wormgear 34, which is mounted on an axis between the upright struts. The worm-gear is provided with a circumferential groove, in and around which is laid a wire rope 35. The said rope passes over suitable 80 guide pulleys at the front and rear of the lower frame and is attached to the ends of the gondola, so that the same can be moved in one or the opposite direction according to the motion of the handwheel. Any kind of ballast can be placed in the gondola.

The horizontal and vertical steering of 90 the aeroplane can be accomplished more quickly and effectively by the mechanisms shown and described in my Patent No. 876,125, which are driven by the motor of the apparatus and which devices I intend 95 to employ in this apparatus.

I will now describe the means for automatically maintaining the equilibrium of the aeroplane and how the lifting effect of the planes is increased. 100

When the propellers force the inclined planes against the air, the air strikes the surface and is deflected downward, rushing in the opposite direction toward the rear of the aeroplane. As there was power applied 105 to move the air stratum from the front edge toward the rear edge, the air will flow out over the rear edge with certain velocity. When the inclined plane cuts and deflects the air downward, the atmospheric pressure 110 above the plane is decreased, the air sinks and glides down over the upper convex surface of the plane. The air under the plane being deflected downward is compressed and has the tendency to flow over the rear 115 edge of the plane in an upward direction. The air stream from above the plane changes, the direction of the air stream coming from below the plane, both streams uniting with the tendency to rush gradually upward. As the plane is driven against the air continuously, the air stream is deflected to an oblique direction, whereby the combined air streams strikes the front part of 120 the next plane. 125

The second plane, being placed higher above the horizontal than the front plane, receives a quiet layer of air from above the front plane and at the same time the obliquely rushing air stream which has already 130

passed over the front plane. As the oblique air stream strikes the second plane at a higher angle producing thus more lift, the angle of incidence of the second plane can 5 be smaller and requires therefore less power to be driven against the air.

The distance between the planes gives the air stream time to develop certain velocity.

The third plane, being placed higher 10 above the horizontal than the second receives again a quiet layer of air from above the second plane and the air stream which passed over the first and second plane. The air which passed over the second plane has 15 smaller velocity than that which passed over the front plane but the moving mass of air and the intermediate space between the planes is larger producing thus more lift and requires smaller angle of incidence, 20 which requires again less power.

Also the fact that the propellers revolve in the rear plane, thus producing suction, adds greatly to the sustaining capacity of the rear plane.

25 As the inertia of the air is more effective than the velocity, the planes placed toward the rear of the aeroplane are of increased area. This arrangement of planes is first to secure longitudinal stability of the aeroplane 30 automatically, because all windgusts striking the first planes strike all other succeeding planes whereby the lifting effect is equalized.

The other advantage of this arrangement 35 is to increase the lifting capacity per horsepower. Motor energy was spent to drive the plane at a given angle of incidence against the air. Only a fraction of this energy can be changed into actual work on 40 a single plane and the rest is taken off by the air in the form of velocity to the succeeding planes where it is utilized.

As the inclination of the plane diminishes 45 toward its tips the air will have the tendency to leave the plane where the inclination is the least. This will cause that more air escapes near the tips of the planes and more rapidly than in the middle of the plane. The rear edges of the plane are placed at a dihedral 50 angle to each other. These arrangements serve to maintain the lateral stability of the aeroplane.

Also the fact that the planes have their 55 largest area in the middle in the line where the propellers revolve and that the rudder is placed in front while the propellers are in the rear of the aeroplane, serve a great deal to maintain the lateral stability.

The tips of the planes having sharp points 60 split the windgusts before they can strike the plane.

Another advantage of the apparatus is that the flow of the air from one plane to the other is not interrupted or disturbed by 65 the propelling devices, being therefore more

efficient; further the propellers revolve under a plane thereby preventing the air from falling from above the aeroplane into the revolving wings of the propeller thus producing more suction. The whirls of air 70 from the propellers do not strike any surface, which also increases the efficiency of the aeroplane.

A wire cable 36 which is fastened to the supporting main-frame connects the tips of 75 the planes, holding thus the planes in given position with respect to the center of the apparatus.

To increase the supporting area of the aeroplane without increase of size of the 80 apparatus, I intend to employ groups of superposed planes arranged in series and having a plurality of planes of the same shape and inclination as the single plane at the location of which the group of planes 85 is placed.

The planes of the middle group are set wider apart than in the front group and in the rear group wider than in the middle group.

90 The planes in each group are placed in such a way that the air current which strikes the planes in one group is caught up by the planes of the next group.

The planes of the rear group are cut out 95 on account of the propellers and the last surface is replaced by a short plane above the upper propeller, like that in the single plane apparatus.

The supporting frame, the steering and 100 propelling of this type apparatus remain the same as in the single plane aeroplane.

The running gears 37 and the floats 38 give the aeroplane facilities to start or alight on firm ground or water.

105 For small size apparatus only one propeller can be employed, arranged so that the thrust comes through the line of resistance of the aeroplane. The shifting of the gondola serves also to adjust the center of 110 gravity to the center of pressure.

Having thus described my invention I claim as new and desire to secure by Letters Patent:

1. In a flying machine, the combination of 115 a supporting frame, a plurality of sustaining planes attached in succession and gradation to said frame, the front plane being in normal flight the lowest, the succeeding planes being placed higher above the horizontal than the front plane, the angle of incidence of the planes being different, said planes being longitudinally spaced from each other, and means for driving the planes against the air.

120 2. In a flying machine, the combination of a main supporting frame, a plurality of sustaining planes attached in succession and gradation to said frame, the front plane being in normal flight the lowest, the suc- 130

ceeding planes being placed higher above the horizontal than the front plane, the angle of incidence of the planes being different, said planes being longitudinally spaced from 5 each other, a propeller for driving said planes against the air mounted in the rear of said frame, and means for actuating said propeller.

3. A flying machine having a supporting 10 frame a plurality of sustaining planes attached gradiently thereto, the front plane being normally the lowest one, said planes being spaced longitudinally from each other, two superposed propellers mounted in the 15 rear of said frame below and above the rear plane in combination with means for driving said propellers.

4. A flying machine having a plurality of 20 gradiently arranged supporting surfaces extending upward toward the rear, said surfaces being of different area and having different angles of incidence, in combination with means for driving said planes against the air.

25 5. In a flying machine having a supporting frame, a plurality of fixed sustaining planes of different area attached thereto, and extending gradiently upward toward the rear of said frame, the angle of incidence of said planes being different on each plane and means for propelling said planes against the air.

30 6. In a flying machine, a supporting frame, a plurality of sustaining planes attached gradiently thereto, the front plane having the largest angle of incidence and the angle

of incidence of the successive planes decreasing to the rear in combination with means for propelling said planes against the air.

7. In a flying machine, the combination of 40 a supporting frame, a plurality of gradiently arranged sustaining planes extending upward toward the rear attached to said frame, said planes being spaced longitudinally from each other, the spaces between the 45 planes being gradually increasing toward the rear, and means for driving the planes against the air.

8. A flying machine having a supporting 50 frame, groups of superposed planes attached thereto, the planes in each group being spaced vertically from each other and the vertical space increasing in each group toward the rear of the machine, the angle of 55 incidence of the planes in each group being different in each group and means for driving said groups of planes against the air.

9. In a flying-machine a sustaining plane having parallel crossribs, said ribs having 60 hulls on both ends adapted to support the marginal spars of said plane, clamps holding the said spars in said hulls, the opposite ends of each rib being connected by a tension wire substantially as set forth and specified.

65 In testimony that I claim the foregoing as my invention, I have signed my name in the presence of two subscribing witnesses.

FRANZ WONDRA.
